J. H. DAVIS,
FLUSH VALVE MECHANISM,
APPLICATION FILED JULY 19, 1909.

970,471.

Patented Sept. 20, 1910.

UNITED STATES PATENT OFFICE.

JOHN H. DAVIS, OF HAMILTON, OHIO.

FLUSH-VALVE MECHANISM.

970,471.

Specification of Letters Patent. Patented Sept. 20, 1910.

Application filed July 19, 1909. Serial No. 508,426.

To all whom it may concern:

Be it known that I, JOHN H. DAVIS, a citizen of the United States, residing at Hamilton, Butler county, Ohio, have invented certain new and useful Improvements in Flush-Valve Mechanism, of which the following is a specification.

This invention, pertaining to flush valve mechanism will be readily understood from the following description taken in connection with the accompanying drawing in which:—

Figure 1 is a side elevation, part vertical section, of a flush valve mechanism exemplifying my invention: Fig. 2 a rear elevation of the same: and Fig. 3 a front elevation of the mechanism.

In the drawing:—1, indicates the wall of a flush tank: 2, an opening through the same: 3, a bushing inserted in the opening in the wall and having a head exterior to the tank wall: 4, a plate screwed upon the inner end of the machine and serving to clamp the tank wall tightly between the plate and the head of the opening: 5, a vertical guide-rod disposed in the tank, in the general vertical plane of the bushing, this guide-rod to have its lower end secured in the base structure of the flush valve in a known manner: 6, an arm projecting rearwardly and rigidly from plate 4 and having the upper end of the guide-rod firmly secured to it: 7, a spindle journaled in the bushing: 8, a handle on the upper end of the spindle: 9, an arm firmly secured to the inner end of the spindle: 10, a stop projecting rearwardly from plate 4, in the path of arm 9, and serving to limit the downward movement of arm 9, arm 6 serving in the present case as a stop to limit the upward motion of arm 9. 11, the usual tubular stem of the flush-valve, this stem having its upper end contracted and fitted to slide on guide-rod 5: and 12, a link connecting arm 9 with the stem of the flush-valve.

The flush-valve stem 10 is illustrated as of the not unusual type in which ports at its upper end fit the stem for duty as an overflow valve. By rocking handle 8 downwardly arm 9 is raised and with it the stem of the flush-valve, in an obvious manner. Arm 6 projecting from the plate furnishes a secure top anchorage for the guide-rod without the necessity for providing a special projection inwardly from the wall of the tank. In the case of metallic tanks it is not easy to provide such special anchorage for

the guide-rod, but in the present case the mere act of clamping the bushing to the tank wall furnishes at the same time a proper anchorage for the top of the valve-rod. By this construction a single opening in the tank wall becomes of avail in securing the moving parts of the valve-operating mechanism in position and at the same time provides the anchorage for the valve rod. Furthermore, the valve-rod co-operates with the plate, through the medium of arm 6, in preventing undesired rotation of the plate while the bushing is being screwed into it, and even if the clamping should become a trifle loosened, it still remains impossible for the plate to become angularly disposed. In the particular construction illustrated, arm 9 is secured to the inner end of the spindle by being fitted to a square on the inner end of the spindle and held thereto by a nut. In the present case, by reason of the presence of inwardly projecting arm 6, no special up-stop need be provided for arm 9.

The improved construction, when fully availed of, provides for the simple connection of a flush valve mechanism with the wall of a tank, regardless of whether that tank be of wood or of metal, a single hole of comparatively small size being all that is required in the wall; it provides for a substantial anchorage for the upper end of a guide-rod, thus adequately taking care of any side strain upon the valve stem which is actuated by the mechanism; and it provides for any desired degree of leverage from the handle, whereby flush valves more or less difficult to lift may be readily operated by children.

I claim:—

1. Flush valve mechanism comprising, a tank wall provided with an aperture, a bushing disposed in said aperture, means for securing the bushing rigidly in the aperture, a spindle journaled in the bushing, a handle on the outer end of the spindle, an arm on the inner end of the spindle adapted for connection with a flush valve part to be lifted, a plate screwed upon the inner end of the bushing, a stop carried by said plate and serving to limit the angular motion of said arm, and an arm projecting inwardly from said plate and adapted to serve as an anchorage for the top of a guide-rod, combined substantially as set forth.

2. Flush valve mechanism comprising, in combination with a tank wall provided with

an opening, a bushing disposed in the opening, means for rigidly securing said bushing in place, a spindle journaled in the bushing, a handle on the outer end of the spindle, an arm on the inner end of the spindle adapted for connection with the movable part of the flush valve, a plate secured on the inner end of the bushing on the inside of the tank, and provided with an arm projecting inwardly and adapted to serve as an anchorage for the upper end of the guide-rod of the flush valve.

3. Flush valve mechanism comprising, in combination with a tank wall provided with an opening, a bushing disposed in the opening, means for rigidly securing said bushing in place, a spindle journaled in the bushing, a handle on the outer end of the spindle,

an arm on the inner end of the spindle adapted for connection with the movable part of the flush valve, a plate secured on the inner end of the bushing on the inside of the tank, and provided with an arm projecting inwardly and adapted to serve as an anchorage for the upper end of the guide-rod of the flush valve, said arm adapted to limit the upward movement of the arm on the inner end of the spindle, and a stop also carried by the plate and adapted to limit the downward movement of the valve operating arm.

JOHN H. DAVIS.
